DISPLAY CARTON

Ralph N. Leonard, Crystal Lake, Ill., assignor to The Radion Corporation, Crystal Lake, Ill., a corporation of Illinois

Filed Aug. 7, 1959, Ser. No. 57,099

Term of patent 14 years

(Cl. D58—12)

Fig. 1 is a perspective view taken from the upper left front corner showing a carton incorporating my new design;

Fig. 2 is a perspective view taken from the upper right front corner thereof;

Fig. 3 is a left side view thereof;

Fig. 4 is a right side view thereof;

Fig. 5 is a front elevational view thereof;

Fig. 6 is a top view thereof; and

Fig. 7 is a bottom view thereof.

The back of the carton is plain and unornamented.

I claim:

The ornamental design for a display carton, substantially as shown and described.
